UNITED STATES PATENT OFFICE.

CHARLES TIMOTHÉE MAXIMILIEN VALERAND DE BANGE, OF VERSAILLES,
FRANCE.

MOUNTING OF RAILWAY OR TRAMWAY ROLLING-STOCK.

SPECIFICATION forming part of Letters Patent No. 758,233, dated April 26, 1904.

Application filed April 7, 1903. Serial No. 151,466. (No model.)

To all whom it may concern:

Be it known that I, CHARLES TIMOTHÉE MAXIMILIEN VALERAND DE BANGE, retired colonel of artillery in the French army, a citizen of the Republic of France, residing at Versailles, in the Republic of France, (whose full postal address is 29 Rue des Marais, Versailles, aforesaid,) have invented certain new and useful Improvements in the Mounting of Railway or Tramway Rolling-Stock, (for which application has been made in France, filed February 19, 1903; in Germany, filed March 11, 1903, and in Great Britain, filed March 23, 1903,) of which the following is a specification.

This invention has for its object improvements in the rolling-stock of railways and tramways.

The rolling-stock of the present railways, while satisfactory when running in a straight line and on a track in perfect condition, becomes defective on curves even of large radius and on a track in the ordinary condition of maintenance. The principal drawbacks are: The two wheels of a pair being keyed on the same axle on a curve, the number of revolutions of the wheels is not proportionate to the distance traveled, from which it results that one wheel slips on the rail; on curves the wheels are not tangential to the track, the result of which is that the wheel-flanges cut the rail; by reason of the axles being parallel there is extreme difficulty in passing over curves of small radius and the consequent impossibility of constructing lines cheaply for light traffic; high cost of traction, owing to the resistance in passing over curves and the wear of tires; inequality in the distribution of the load on the wheels while running, increased by the inevitable position of the grease-boxes on the outside, by which a wheel is thus apt not only to be relieved of its load, but also raised from the track, from whence arise the many unexplained derailments, (the unknown cause of accidents;) by reason of defects in the track the load is not equally distributed over the four wheels of the vehicle, but frequently bears on two wheels diagonally, the result of which is that one wheel may be raised, and if the wheel raised is the

one which guides the vehicle it is easy for it to mount the rail, and hence cause derailment. In any case there is a constant pounding of the tires on the rails, causing them to wear away and also increasing the resistance to the movement. These difficulties would disappear if we possessed a method of convergence or of keeping the wheels tangential to the rails, which at the same time would be safe, and if the axles remained constantly weighted or loaded at their centers, or approximately so. In order to attain these desiderata, the rolling-stock must fulfil the following conditions: Each wheel should be mounted on an independent axle, as in this way the revolutions of the wheels are always proportionate to the distance traveled. For railway-trains it is not practical to mount the wheels loosely on the axles like the wheels of a road-carriage, because of the difficulties of lubrication. For wheels with inner flanges each wheel must turn on a vertical axis situated (from a point between the wheels) outside of the tread of the respective wheels. The axle must therefore be divided and each wheel arranged independently. The vertical pivots about which the respective wheels of a pair turn may be located on perpendiculars at the same distance from the axis of the vehicle or may even be placed at different distances. With outer flanges each wheel must, on the contrary, turn on a vertical axis situated between the two wheels of a pair. The axle may therefore remain entire for a pair; but it is preferable to mount the wheels on separate axles in order to facilitate the converging movement and avoid, to a certain degree, resistance to the traction.

It is seen from the above that the vertical pivot of each wheel must always be situated on the opposite side of the tread of the wheel from the flange. This is the principal point. Any other method of convergence or turning of the wheels is liable to cause derailments. If the conditions hereinbefore mentioned are fulfilled, the convergence or turning will be effected with great safety and allow of the distance between the axles being increased as desired, the radius of the curves being reduced

in proportions greater than actually required and the costs of traction to be diminished. The loading of the axles must be arranged so that the load shall always be distributed in the 5 same manner as if it rested on the middle of two axles at points situated above the center of gravity of the load and so that the load may oscillate without making the axles themselves turn on a horizontal axis passing through 10 the points of support and parallel to the axis of the track, and vice versa, so that the wheels may pass over inequalities in the track without oscillating the load. This results from the arrangement by which the load always 15 bears on the center of each pair of wheels and from the vehicle-body being suspended by means of a horizontal axis situated in a longitudinal mean plane above the center of gravity of said body, the vehicle-body being free 20 to oscillate on said axis. The vehicle has very great stability, because it is suspended above its center of gravity, and it can oscillate upon its axis of suspension. It is in stable equilibrium, because the weight of the vehicle 25 tends to always return it into a vertical plane. This arrangement, which consists in suspending the vehicle by its longitudinal axis, while permitting it to oscillate on its longitudinal axis, has also the advantage that 30 transverse jolts due to inequalities of the track in plan and to the play between the flange and the rail, and which are received by the flanges of the wheels, have not time to be transmitted to the mass of the vehicle, which 35 is not rigidly connected with the axles of the wheels. It is seen from this that the two wheels of each pair are always approximately equally loaded; but it must not be understood that the four wheels of the vehicle are equally 40 loaded, but only the two wheels of the same pair of wheels. This is produced by the load always resting on the middle of the cross-bar approximately on a vertical line midway between the two wheels.

45 In the description of the invention it is always assumed that the vehicle is carried on four wheels; but for very heavy vehicles it may be necessary that each end of the vehicle should rest on four wheels.

50 The invention consists in combining the vertically-pivoted wheels and horizontally-pivoted wheel-trucks and vehicle-body, as described. The points of support, as well as the axis of oscillation, may be imaginary, provided that things take place as if they existed. The realization of this condition, which is almost impossible with the rolling-stock at present employed, is especially facilitated by the convergence or turning of the wheels, which 55 enables the axles to be separated and allows the body of the vehicle to be lowered to fifteen or twenty centimeters above the rails. In the case of a vehicle which would in ordinary course have more than two axles one of the points of 60 support will be the middle of a balancer or

equalizing-bar the extremes of which rest, respectively, on two axles at two points always placed in a straight line with their middle above the center of gravity of the load, with a freedom to oscillate on an axis parallel to the axis of the 70 track. The realization of this condition by invariably insuring a division and distribution of the load on the wheels will render the lifting of any of the latter impossible, as no one wheel can be entirely relieved of its load, and will thus 75 prevent accidents which are unforeseen and are not caused by the staff, and one result of this and of the convergence or turning of the wheels will be that the running will be easier, more particularly on entering on a curve, and 80 the wear of the tires will be much reduced. These conditions may be fulfilled in the manner hereinafter indicated, which applies to the different cases which may arise—i. e., when the flanges are internal or external, the material new, the existing material is to be transformed with electric traction or traction by 85 locomotive. The arrangement is shown in the accompanying drawings, in which for the sake of clearness only the parts are shown which 90 are necessary to enable the nature of the invention to be understood, details of construction which are known to persons conversant with railway management being omitted.

Figure 1 is a plan view, Fig. 2 a transverse elevation, and Fig. 3 a longitudinal elevation, of an arrangement with internal flanges. Figs. 1bis and 2bis are similar views to Figs. 1 and 2 and show the arrangement with external flanges. Figs. 4 and 5 are diagrammatic 100 plan views showing the positions which the axles of the wheels may assume when the flanges are internal and when the flanges are external, respectively. Figs. 6, 7, and 8 are partial views with certain parts in section in 105 plan, transverse elevation, and longitudinal elevation, respectively, showing a convenient arrangement for the conversion of existing rolling-stock. Fig. 9 is a partial plan view of the axis of suspension. Fig. 10 is a longitudinal vertical section of the part shown in Fig. 9. Figs. 11 and 12 are transverse and longitudinal sections of a modification in the application of the invention. Fig. 13 is an elevation and transverse section of a half-axle, 115 showing the invention as adapted to locomotives. Figs. 14, 15, and 16 are details of transmission in plan view, in transverse elevation, and longitudinal elevation, respectively. Figs. 17 and 18 show an arrangement suitable 120 for two pairs of wheels and axles.

Referring to Figs. 1, 2, 3, 1bis, 2bis, 4, and 5, the box or body 1 and its frame 2 are lowered to about 15 to 20 centimeters above the rail, and the frame is consequently prolonged at 3. 125 Each wheel is formed of a solid part 4, forming one with a half-axle 5 forged with it. (It is of course evident that the wheel might be keyed on this half-axle in the ordinary manner.) The load is transmitted by means of a 130

cross-bar 6, weighted at the center 7 to the two bearings 8 and 9 of each half-axle 5. The bearings 8 have a spindle or projection which engages in the cross-bar 6. As shown in Fig. 2, the axis of the spindle 10 lies in the line X X for an internal flange, and in Fig. 2bis the axis of the spindle 135 lies in the line Y Y for an external flange, and it is this trunnion which allows the convergence or turning of the wheel. The center of the bearing 8 is located at a certain distance from and outside the vertical line passing through the center of the tire in order to insure a given distribution of the load between the journal 11 and the journal 12. The bearing of the journal 12 has a nipple or projection 13, which slides in a circular groove 14, formed in the under part of the cross-piece 6. The center from which said groove is described is on the axis X X or Y Y, respectively. The cross-piece 6 is guided in guard-plates 15, connected at their upper part by cross-pieces 18 and fixed at their lower part to the longitudinal internal cross-bars 16, attached to transverse cross-bars 17 of the frame. These guard-plates guide the lower part of the cross-bar. The head of the upright 7 of the cross-bar 6 forms a bearing for the cylindrical heel 20 of the yoke of a transverse spring 21, the ends of which are fixed to links 30 attached to the uprights 22 and cross-bar 23, the latter being attached to the box or body of the vehicle by a piece 24 riveted thereon. The center of the heel or supporting piece 20 is placed above the center of gravity of the suspended part. The upper part of the upright 7 of the cross-piece 6 is guided by the parts 23 and 24 by means of two slides 25, fitted on prolongations 26 of the cylindrical heel 20. There are some millimeters of play 40 between the head of the upright 7 and the aperture formed for its passage in the parts 23 and 24. In this manner play is given for vertical oscillation and the rotation of the suspended part on the free horizontal axis of the heel-piece 20 parallel to axis of the vehicle.

Figs. 6, 7, 8, 9, and 10 show an arrangement suitable for converting existing rolling-stock. The axis of turning of the wheel X X is in the center of the external grease-box. The cross-piece 40 extends beyond the wheels and is supported on the external grease-box 41 by means of its struts or bars 43 and the internal grease-box 42 by struts 44, these struts or bars being firmly attached to their respective grease-boxes. The grease-box 42 is guided below by guard-plates 45, engaging over the bottom of the upright 44, while the grease-box 41 is guided by the guard-plates 47, fixed to the longitudinal bars of the frame transmitting the load to the transverse spring 48. The guard-plates 47 guide the cross-bar 40 in a longitudinal direction and allow it to move laterally. The grease-box 41 is covered with a plate 49, which fits over it, and has a hole cut therein, the center of which is on the line X X.

A vertical cylindrical shaft 50, fixed at its upper end to the cross-bar 40, engages in this hole. In this manner the turning of the wheel and its half-axle on the axis X X of the external grease-box is insured. The shaft 50 further serves as support to brake-pieces, as will be shown hereinafter. A spring 48 bears on the top of the internal upright 44, the method of support, which is easily understood by examining Figs. 7, 9, and 10, being the same as that described with reference to Figs. 2 and 3.

Figs. 11 and 12 show an arrangement which is solely applicable to external flanges where the turning of the wheels is about an internal axis Z Z and also about a horizontal axis parallel to the axis of the track. With internal tires this would involve certain derailment, as the play would be limited to a few millimeters between the flange and the rail. A central journal of an axle 55 receives the load through a large grease-box 56, to which it is transmitted by an upright 57, the spherical top of which is embedded in a socket on the yoke of the spring, so that the turning movement is effected about one point. The lower part of the grease-box carries a spindle 58, which travels in a slide 59, the ends of which are fixed to the cross-bars of the frame, and which prevents the upright 57 from moving in the direction of the track. The head of the upright 57 is guided as in the previous case by a cross-piece 51, fixed to uprights 47, themselves secured to the longitudinal bars of the frame and by a piece 52, riveted to the box or body of the vehicle. These two parts have a free vertical movement, owing to a bearing 60, which incloses the exterior of the socket of the spring. The spokes of the wheels have a special form which gives them great elasticity. The wheels are firmly attached to two hubs 61, loosely mounted on the axle 55. These hubs fitted on the axle are maintained there by pinned nuts 62. In this arrangement the axle turns, carrying with it the wheels, and as the friction of the hubs is comparatively great they only move when passing over curves in order to compensate the difference in the distance traveled by the wheels.

In these improved arrangements the brakes are arranged in the following manner: As the wheels turn about a vertical axis, it is of course necessary to place the brake-shoe above the wheel, fixing it in such a way that it can turn on the axis X X and Y Y, Fig. 2. This arrangement is preferable, because it does not interfere with the effect of the suspension. Fig. 2 shows a brake-shoe 65, pivoted on an arm 66, turning on a bolt dependent on a collar 67, adapted to turn on a vertical axis 7, passing through the axis of suspension. Further, a circular spindle or projection 68, fixed to the brake-shoe, the center of which is on the axis X X, engages in a circular recess or aperture in the rod 66. This bar is

actuated by any suitable known means. It is therefore needless to describe it. In the case of external tires the axis of this spindle is on the axis Y Y. Fig. 7 shows the brake-shoe 5 guided by the shaft 50, which forms the axis about which the wheel turns and supported by a rod 70, engaging in the plate 49, which covers the grease-box. Fig. 11 shows a similar arrangement to the one described in connection with Fig. 2, with the difference that the whole mechanism turns with the upright 57. The movement is given by known means, and therefore need not be described. The air-reservoirs of the brake may easily be located near the axle.

As regards the coupling, it is preferable to have only a single central buffer, as shown, for instance, in Figs. 7 and 8. The buffers need not be compressed but simply in contact, because in this arrangement the vehicle is stable and guides itself and does not require to have its movements restrained by the next vehicle. Compression would therefore be rather deleterious. Having only a central buffer, any of the ordinary types may be employed, and preferably one in which the buffer and coupling are integral.

The parts 24 of Fig. 2 or 52 of Figs. 7 and 8, which connect the top of the uprights of the box or body, have the advantage of connecting this box or body to the frame in the upper part. The concussion-spring may therefore be arranged either against the box or against the frame. In case of collision the frame and the box resist together and are capable of standing at least double the strain to that of which the frame alone is capable of doing. The reason this arrangement has not been adopted in the present rolling-stock is owing to the height of the box or body, which renders it difficult. Even if the frame is not broken the boxes are apt to rise and smash one against the other.

On examination of the foregoing it is easy to see that the application of electricity would be easy, because plenty of room exists for freely fixing the apparatus to the frames of the axles. I do not require to describe the installation of such, because it would be done by means already known. It must be noted, however, that as the moving parts placed are no longer under the body of the vehicle but within view of the official at the end of the vehicle they are easily inspected. As the axle of the frame may be withdrawn without lifting the wagon more than ten to twenty centimeters, all the parts of the mechanism may be easily removed, which parts are independent of the frame and of the box or body.

In order that the description of the system which has just been explained may be complete, it is only necessary to show the arrangements adopted for wagons suitable for use with locomotives. It suffices to show that the motion may be transmitted by a crank to a convergent wheel and that the suspension

may be arranged in such a way that each axle shall be under the same conditions as if it were weighted at its center, the center of gravity of the suspended part being above the heel-pieces or center blocks of the spring. 70

Referring to Figs. 13, 14, 15, and 16, a solid wheel 80, formed in a single piece with its hollow half-axle, is fitted with a tire, or a wheel is used of ordinary form but of larger diameter which carries its tire. The axis Y Y 75 about which the wheel turns placed in the middle of the tire is the same for both internal and external flanges. The turning takes place about an upper spindle or projection 90 and a lower spindle 91. The load is transmitted by a cross-piece 88, which rests on the grease-boxes 94 and 95. The spindle 91 engages in a secondary piece 89, intended to increase the rigidity, but it is not indispensable. The cross-pieces 88 and 89 are guided between guard-plates 96. The hollow half-axle is allowed enough play for the convergence or turning of the wheel by a false axle 81, which carries a journal and bearings 97 at its center guided by a guard-plate 93, which 80 maintains the center of the axle in the axis of the machine. On this false axle at each end double bent arms 82 are keyed, the ends of which are circular in section and engage in an aperture formed in the body of the wheel. 95 On these cylindrical ends are spheres or the like 83, inclosed by a bearing formed in three pieces 84^a 84^b 84^c, the spheres being fitted with slight friction. The bearing 84^a has a spherical surface 85 perpendicular to the radius of the wheel, of which 0 is the center, and in addition on a face of similar form in the aperture. The two other parts 84^b and 84^c of the bearing rest with their external faces on flat faces 86 of the aperture parallel to the radius from 0 to the center of the sphere 83 and perpendicular to the plane of the wheel. The false axle is thus by its double arms centered on the wheels at each side by the faces 85 and maintained in position by the two faces 85 and 86. It is also evident that it also has some lateral play owing to its ends being capable of sliding in the spheres 83. The result of these arrangements is that the wheel can turn on the axis Y Y or 100 an axis which would be perpendicular to it or intermediate axes between these two without carrying the cranks with it. There is no rigidity between these parts except for rotation on the horizontal axis of the false axle. The lateral faces 86 cause this wheel to be carried along in the rotation of the cranks whatever angle the wheel may form with the false axle. It is evident that ordinary means 110 for adjusting or fitting (keys and the like) are 115 applicable for connecting the cranks with their bearings and these bearings with the faces of the aperture. Each crank has two lateral tenons 100, intended to facilitate the unkeying action. The journals receive the 120

load through the cross-piece 88, on which rest supports 101, carrying strip-springs 102, parallel with the axis of the engine. The heel-piece of the yoke of the spring resting on the 5 post is spherical. The support is maintained vertical by a cross-piece 103, fixed to the longitudinal bar 104 of the frame, which cross-piece can slide freely in a vertical direction on the support. The heels or points of 10 support of the springs are placed above the center of gravity of the suspended portion of the engine. Each spring has one suspension-rod attached to the longitudinal bar of the frame and the other to the end of a transverse 15 balancer, the center of which is carried by one or two cross-bars of the frame.

The arrangement hereinbefore described is applicable to a single axle. Figs. 17 and 18 show that if the load is to be equally distributed over two axles the internal suspension-rods 105 are fixed to a longitudinal balancer 110, and the other end rods 106 are fixed, respectively, to transverse balancers 111, the 20 center of which is attached to cross-bars connecting the longitudinal bars of the frame. Under these conditions each spring has one of its ends attached to a transverse balancer and the other to a longitudinal balancer. If the 25 wheels are of unequal diameter, the support attached to the smaller one is longer, so that all the heels or center blocks of the spring are always on the same horizontal plane P P, situated above the center of gravity G of the suspended part.

35 I declare that what I claim is—

1. In railway and tramway vehicles, the combination of a vehicle-body, a cross-bar adapted to support one end of said body, said cross-bar having a central upwardly-extending 40 column and a socket at the top of said column, two supporting-wheels each having a flange and each having a half-length axle extending therefrom and integral therewith, each of the said wheels and its axle being 45 adapted to turn on said cross-bar about a vertical axis situated at the opposite side of the tread of said wheel from the flange, a cylindrical heel-piece, and a transverse suspension-spring, said spring supporting the vehicle- 50 body at its ends and secured at its center to said heel-piece, said heel-piece lying transversely to said spring and being pivotally supported in said socket, said heel-piece being located above the center of gravity of said body, 55 and said body being free to oscillate sidewise on said heel-piece.

2. In railway and tramway vehicles, the combination of a vehicle-body, a cross-bar adapted to support one end of said body, said 60 cross-bar having a central upwardly-extending column and a socket at the top of said column, two supporting-wheels each having a flange and each having a half-length axle extending therefrom and integral therewith, 65 bearings between the ends of said cross-bar and

said axles and adjacent to said wheels, each of said bearings having a vertical spindle thereon pivoted in the end of said cross-bar, said vertical pivot being situated at the opposite side of the tread of each wheel from the flange, 70 a cylindrical heel-piece, and a transverse suspension-spring, said spring supporting the vehicle-body at its ends and secured at its center to said heel-piece, said heel-piece lying transversely to said spring and being pivotally supported in said socket, said heel-piece being located above the center of gravity of said body, and said body being free to oscillate sidewise on said heel-piece.

3. In railway and tramway vehicles, the combination of a vehicle-body, a cross-bar adapted to support one end of said body on a horizontal pivot above its center of gravity, said body being free to oscillate sidewise on said pivot, two supporting-wheels each having 80 a flange and each having a half-length axle extending therefrom and integral therewith, bearings between the ends of said cross-bar and said axles and adjacent to said wheels, each of said bearings having a vertical spindle 85 thereon pivoting in the end of said cross-bar, said vertical pivot being situated at the opposite side of the tread of each wheel from the flange, said cross-bar having arcuate tracks on its underneath side, and bearing-blocks 90 adapted to slide in said tracks and to receive the free ends of the respective axles.

4. In railway and tramway vehicles, the combination of a cross-bar, supporting-wheels whose axles are mounted on vertical pivots in 100 the ends of said bar, a vehicle-body, a transverse suspension-spring pivoted to the middle of said bar at a point higher than the center of gravity of said body, a frame suspended on said spring and secured to said body, said 105 spring and frame and body being free to oscillate in the direction of the length of the spring, cross-pieces on the under part of said frame, and vertical guides carried on said cross-pieces, said guides being located on either side 110 of the said cross-bar and adapted to prevent any oscillation of the vehicle-body in a longitudinal direction.

5. In railway and tramway rolling-stock, the combination of two-wheeled trucks, a body 115 supported on said trucks by longitudinal horizontal pivots above its center of gravity, said body being free to oscillate sidewise on said pivots, said pivot being in each instance on a vertical line midway between the wheels of 120 each pair, whereby the load is approximately equally distributed between the two individual wheels of each pair, and means enabling the wheels to automatically place themselves so that their axles are in the direction of the radius of the track.

6. In railway and tramway rolling-stock, the combination of two-wheeled trucks, a body supported on said trucks by longitudinal horizontal pivots above its center of gravity, said 130

body being free to oscillate sidewise on said pivots, said pivot being in each instance on a vertical line midway between the wheels of each pair, whereby the load is approximately 5 equally distributed between the two individual wheels of each pair, said supporting-wheels having flanges, and axles for said wheels, each of said axles being mounted on a vertical pivot and free to turn thereon within certain limits, 10 said vertical pivot being situated at the opposite side of the tread of said wheels from the flanges.

7. In railway and tramway rolling-stock, the combination of two-wheeled trucks, a body 15 supported on said trucks by longitudinal horizontal pivots above its center of gravity, said body being free to oscillate sidewise on said pivots, said pivot being in each instance on a vertical line midway between the wheels of 20 each pair, whereby the load is approximately equally distributed between the two individual wheels of each pair, said supporting-wheels having flanges, and an individual axle for each of said wheels, each of said axles being mounted 25 on a vertical pivot and free to turn thereon within certain limits, said vertical pivot being situated at the opposite side of the tread of said wheel from the flange.

8. In railway and tramway rolling-stock, 30 the combination of trucks having supporting-wheels, a body mounted on said trucks on longitudinal horizontal pivots above its center of gravity, said body being free to oscillate sidewise on said pivots, said supporting-wheels 35 having flanges, and axles for said wheels, each of said axles being mounted on a vertical pivot and free to turn thereon within certain limits, said vertical pivot being situated at the opposite side of the tread of said wheels 40 from the flanges.

9. In railway and tramway rolling-stock, the combination of two-wheeled trucks, a body supported on said trucks by longitudinal horizontal pivots above its center of gravity, said 45 body being free to oscillate sidewise on said pivots, said supporting-wheels having flanges, and an individual axle for each of said wheels, each of said axles being mounted on a vertical pivot and free to turn thereon within cer- 50 tain limits, said vertical pivot being situated at the opposite side of the tread of said wheel from the flange.

10. In railway and tramway vehicles, the

combination of a vehicle-body, a cross-bar, 55 said cross-bar having a centrally upwardly extending column and a socket at the top of said column, a cylindrical heel-piece pivoted and supported in said socket, said pivot being at a higher point than the center of gravity of said vehicle-body, a transverse suspension-spring secured at its middle to said heel-piece, a frame suspended from the ends of said spring and secured to said body, said body being free to oscillate sidewise on said heel-piece, cross-pieces on the lower part of said 60 frame, vertical guides carried on said cross-pieces, said guides being located on either side of the said cross-bar and adapted to prevent any oscillation of the vehicle-body in a longitudinal direction, two supporting-wheels 65 each having a flange and each having a half-length axle extending therefrom and integral therewith, bearings between the ends of said cross-bar and said axles and adjacent to said wheels, each of said bearings having a vertical spindle thereon pivoted in the end of said cross-bar, said vertical pivot being situated at the opposite side of the tread of each wheel from the flange, said cross-bar having arcuate 70 tracks on its underneath side, and bearing-blocks adapted to slide in said tracks and receiving the free ends of the respective axles. 75

11. In railway and tramway vehicles, the combination of a vehicle-body, two-wheeled trucks supporting said body and each truck attached thereto by a longitudinal horizontal pivot located on a vertical line midway between the wheels of each pair, whereby the load is approximately equally divided between the two individual wheels of each pair, said supporting-wheels having flanges, and an individual axle for each of said wheels, each of 80 said axles being mounted on a vertical pivot and free to turn thereon within certain limits, said vertical pivot being situated at the opposite side of the tread of said wheel from the flange. 90

In witness whereof I have hereunto signed my name, this 21st day of March, 1903, in the presence of two subscribing witnesses.

CHARLES TIMOTHÉE MAXIMILIEN
VALERAND DE BANGE.
